CLAIM

The ornamental design for a wall mounting base with lights, sensor window, and connector for a camera device, as shown and described.

DESCRIPTION

FIG. 1 is a bottom, front, right side perspective view of a wall mounting base with lights, sensor window, and connector for a camera device showing our new design;

FIG. 2 is a top, back, right side perspective view thereof;

FIG. 3 is a front view thereof;

FIG. 4 is a back view thereof;

FIG. 5 is a right side view thereof;

FIG. 6 is a left side view thereof;

FIG. 7 is a top view thereof;

FIG. 8 is a bottom view thereof; and,

FIG. 9 is a bottom, front, right side perspective view thereof with the connector moved down to provide a full view of a front surface thereof.

The broken lines shown in the drawings represent portions of the wall mounting base with lights, sensor window, and connector for a camera device that form no part of the claimed design.
